UNITED STATES PATENT OFFICE

LLOYD V. CASTO, OF DETROIT, MICHIGAN, ASSIGNOR TO THE OXFORD VARNISH CORPORATION, OF DETROIT, MICHIGAN, A CORPORATION OF MICHIGAN

PROCESS FOR THE REPRODUCTION OF THE NATURAL APPEARANCES OF ARTICLES ON OTHER SURFACES

Application filed November 23, 1927. Serial No. 235,196.

This invention is concerned with the art of reproducing or simulating the natural surfaces or appearances of articles such as wood, marble, etc., and has for its general object, the provision of a method of reproducing in accurate tonal detail the contrasting contours and shades of the surfaces of natural bodies upon the surfaces of bodies which are formed of dissimilar materials, the invention being in the nature of an improvement in the photogravure process now being utilized for the reproduction of wood graining upon flat metallic surfaces.

More specifically, my invention is concerned with the production of photogravure rolls or plates in such manner as to obtain practically all of the tonal contrasts of the surface appearance to be reproduced. Other objects of my invention will hereinafter be come apparent from the following description of my method of producing such plates or rolls. The essential characteristics are summarized in the claim.

In the drawings, Fig. 1 represents the first stage of producing a master drawing; Fig. 2 represents the second stage of producing such a drawing, and Fig. 3 represents a completed master drawing.

In order to more clearly set forth my present method of engraving photogravure plates and rolls for the purposes hereinabove set forth, I will first briefly describe the method hereinabove utilized in engraving photogravure plates and rolls for the reproduction of wood grain on smooth hard surfaces of metallic sheets. When it is desired to obtain or reproduce the grain effect or appearance of a quarter oak panel, butt walnut, etc., a wooden panel is first made, the grain of which has been carefully selected for proper grain contrasts and the panel surface is stained with a liquid stain, the color of which has been carefully predetermined to bring about the desired accentuation of the panel grain. The panel is preferably of the same size or dimension as the surface dimension which is to have the grain reproduction effected thereon, and commercial requirements are such that the panels and correspondingly the engraved plates or roll surfaces are usually

not less than 30 x 60" and frequently as extensive in area as 38 x 80". The wooden panel or master panel is then surfaced with a selected varnish to tone the stain previously applied to the grain pores of the wood, and the master panel is then ready for the 55 photographer. The panel is mounted in an illuminating gallery equipped with illuminating means disposed at various angles to effect a uniform illumination of all portions 60 of the stained surface of the panel. 65

An unusually large photographic apparatus is then used to obtain a photographic negative film or plate of the same dimensions as the master panel. A positive is then made 65 from the negative, and from the positive, a carbon resist is made by the interposition of a photographic screen, and the photogravure roll or plate is then etched through the carbon resist in the usual manner. The plate or roll thus made is utilized by applying ink 70 or pigment to the engraved surfaces thereof, the surface ink being removed by the use of a doctor blade, thus leaving ink in the minute pockets of the engraved surface. The pattern is removed from the plate by the use of 75 a gum roll; each minute portion of pigment adhering to the roll surface in conformity with the arrangement of engraving on the plate. The roll is then passed over the surface to be finished or grained, and the pre-arranged pattern is thus transferred thereto. 80

Some striking simulations of natural grains have been reproduced by the foregoing described process, but extreme care 85 must be taken in all of the various steps from the selection of the wood of the master panel to the final operation of transferring the pattern to the surface to be finished. Particular study has been given to the composition of 90 the stain applied to the master board, the glossing of the surface thereof, the preparation of the photographic films or plates before exposure, the functioning of the photographic apparatus, the reproduction of the positive carbon resist, and the character of 95 the etching acids.

Despite all of this effort, some of the quarter tones and half tones present in the original master board are lost due primarily to 100

the lack of light contrast between the back or ground colors of the master board and the full tones accentuated in the ground lights or colors of the stained board, thus necessitating slow tedious hand-engraving or re-touching under a magnifying glass of the minute and relatively shallow pockets which should be present in the final etched plate result, and which are thus lost.

10 I propose, therefore, to first prepare the panel in the manner described, and while using this panel as a subject to prepare a drawing thereof on parchment or paper, the color of which, relative to the grain tones, 15 will provide a marked over-contrast, and then 20 I photograph the drawing and produce the plate by the subsequent steps of the process described, during which the over-contrast is slightly diminished in each of said steps of the process, and in the final etching step, all 25 of the details of engraving will be properly produced on the plate or roll surface to effect the final reproduction of the several fractional tones present in the original master board.

25 In Fig. 1 of the drawings I show the beginning of a master drawing with full tone or outstanding lines 10, which may be effected thereon by manual effort or through photographic means, the coloring of the paper being preferably of a lighter shade than the back or ground color of the master board. I then carefully draw upon this master drawing half tone lines 12, (see Fig. 2) and next 30 carefully produce quarter tone lines 14 and finally lesser contrasting tones 16, this drawing being of the same dimensions as the master board. It is to be understood that if desired the board may be ruled into guiding 35 squares or zones, preferably inch squares, and 40 the paper or parchment drawing correspondingly lightly ruled.

45 I then place the drawing on a mounting means in the illuminating gallery and produce therefrom in the manner described, a full size negative from which positive and carbon resist are made as hereinabove set forth. Each succeeding step gradually decreases the over-contrast and then the etching 50 is effected by the artist upon the plate or roll, and the entire surface is simultaneously etched without necessitating acceleration and retardation of the etching action of the acids over various zones of the surface being etched.

55 A photogravure plate or roll made in the manner described will have screen pockets reproduced thereon which have been heretofore unobtainable regardless of the degree of care exercised in the various operations of 60 producing the plate or roll and in the selection of the various materials used in carrying out the process. For example, in reproducing a butt walnut I may obtain as high as 65 five distinct tonal contrasts in one transfer-ring operation of the pigment from the plate

to the surface to be grained which tonal contrast heretofore has either been lost or so nearly completely subdued in the ground color that the optical effect has been lacking.

I claim:

70 The process of reproducing photogravure plates and rolls which includes the steps of preparing a master drawing of the surface appearance of an article which surface appearance is to be simulated on other articles 75 and forms of dissimilar materials by filling in on the master drawing over-emphasized full tone, half tone, quarter tone and under tone shades corresponding to and in configuration 80 with the full tones, half tones, quarter tones 85 and under tones of the configurations of the surface of the subject whereby said drawing may be utilized to produce a full sized carbon resist by the photographic process and the over-emphasis of the tonal contrasts becomes 90 eliminated in the photographic steps of making the negative, positive and carbon resist.

In testimony whereof, I hereunto affix my signature.
